US0D1065080S

(12) **United States Design Patent** (10) Patent No.: **US D1,065,080 S**
(45) Date of Patent: ** Mar. 4, 2025

(54) **ADAPTER**

(71) Applicant: **Anker Innovations Technology Co. Ltd.**, Changsha (CN)

(72) Inventors: **Yuepei Xing**, Shenzhen (CN); **Yijing Wang**, Shenzhen (CN)

(73) Assignee: **Anker Innovations Technology Co. Ltd.**, Changsha (CN)

(**) Term: **15 Years**

(21) Appl. No.: **29/783,957**

(22) Filed: **May 17, 2021**

(30) **Foreign Application Priority Data**

Feb. 8, 2021 (CN) 202130095537.1

(57) **CLAIM**

The ornamental design for an adapter as shown and described.

DESCRIPTION

FIG. 1 is a front perspective view of an adapter showing the new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines depict the portions of the adapter that form no part of the claimed design.

1 Claim, 6 Drawing Sheets

FIG. 1

FIG. 2

FIG. 3

FIG. 4

FIG. 5

FIG. 6
